UNITED STATES PATENT OFFICE.

HENNING HALLSTREAM, OF EAST BRIDGEWATER, MASSACHUSETTS, AS
SIGNOR TO AMERICAN PAPER FEEDER COMPANY, OF BOSTON, MASSA-
CHUSETTS, A CORPORATION OF MAINE.

SHEET-FEEDING MACHINE.

No. 854,088.

Specification of Letters Patent.

Patented May 21, 1907.

Application filed October 19, 1904; Serial No. 229,079.

To all whom it may concern:

Be it known that I, HENNING HALLSTREAM, of East Bridgewater, in the county of Plymouth and State of Massachusetts, have invented certain new and useful Improvements in Sheet-Feeding Machines, of which the following is a specification.

The present invention relates to improvements in sheet feeding mechanism for conveying sheets in succession from an automatic feeding mechanism to a printing press or other machine for acting upon or manipulating the sheets.

It is frequently desirable in feeding sheets in succession to machines to advance the sheets into position to be acted upon at a high rate of speed and at the same time to leave the sheets accurately in position. For instance in feeding sheets to the front gages of a printing press running at high speed it is necessary to advance the sheets to the front gages at a high rate of speed in order that the side register devices may have time to operate before the sheet is seized by the grippers of the press. If the sheets are brought against the front gages at full speed and the gages are relied upon to arrest the sheet in the proper position, it has been found that either the front edge of the sheet will be crumpled and injured or the sheet will bound away from the front gages and not be properly registered against them, and various mechanism and devices have been devised for slowing down the sheets as they are presented against the front gages.

Certain features of the present invention relate to a novel construction and arrangement of slow-down devices which will enable the sheets to be advanced at a high rate of speed until they are approximately in position and will then act to slow down the sheet and release it when it is either approximately at a state of rest or traveling at so slow a speed that it will be properly positioned against the front gages. This slow-down mechanism consists of delivery rolls or other conveying surface such as tapes for instance, which are driven at a comparatively high rate of speed to advance the sheet until its front edge is near the front gages or the desired position and are then gradually retarded as the rear part of the sheet passes between them so as to gradually slow down

the sheet without changing its alignment just previous to the release of the sheet from the action of the conveying surfaces.

Further features of invention relate to the construction and arrangement of delivery devices which may be readily applied to the feed boards of existing presses for conveying sheets from a sheet separating mechanism arranged at the rear of the feed board and which may be readily thrown out of position above the feed board when it is desired to gain access to the sheet delivery or other devices located under the feed board.

The various features of invention will be understood from the following detailed description of the feeding mechanism shown in the accompanying drawings which embodies all the features in the form in which I prefer to employ them.

In these drawings Figures 1, 2 and 3 show a side elevation of the feeding mechanism. Fig. 4 is a plan view of that part of the mechanism shown in Fig. 2. Fig. 5 is a vertical sectional view on line 5—5 Fig. 4. Fig. 6 is a sectional view on line 6—6 Fig. 2.

In the machine shown in the drawings the sheets to be fed are supported upon a vertically moving table A which presents the top of the pile of sheets to combing devices indicated at B by which the top sheets are separated and fed to delivery rolls C C'. The sheet separating mechanism and the means for controlling it so as to present individual sheets in succession to the delivery rolls C C' may be of any suitable construction such for instance as shown in Patent #690,702 January 7, 1902; and the upper delivery rolls C' may be moved into and out of engagement with the lower delivery roll C' at proper intervals as in the construction shown in said patent.

The sheets separated from the pile on the table A are advanced by the rolls C C' and by a series of tapes D extending from the roll C' around a second tape roll or drum C'. The tape drum C' is mounted in brackets E secured at the front ends of bars E' which are pivoted at E' to the side frames of the feeder. The brackets E are connected by tie rods E' and the brackets, tie rods, and bars E' form a pivoted frame for supporting certain parts of the sheet feeding mechanism. This frame is supported in position above the feed board

F of the press by feet E⁴ extending downward from the brackets E and resting upon the feed board.

The sheets as they are carried along by the tapes D pass between the drum C² and presser rolls C³ arranged to bear upon the sheets above the drum C² and insure their onward movement. The presser rolls C³ are mounted in arms c pivoted to lugs c' depending from collars c² which are adjustably secured upon a rod E⁵ connecting the brackets E. The rear ends of the arms c extend beyond the lugs c' and are curved upward as indicated in Fig. 5 to insure the passage of the front edge of the sheet. By adjusting the collars c² on the rod E⁵ the rolls C³ may be brought into the desired position with relation to the tapes D.

The tapes D deliver the sheets onto a series of supporting bars G and between the conveying surfaces of the delivery rollers H, I by which the sheet is advanced along the bars G, and delivered with the front edge against the front gages J of the press. During the advance of the sheet from the tapes D to a position where the front edge of the sheet is near the front gages J the delivery roll I is driven at the same speed as the tapes so that the sheet is rapidly and continuously advanced. As the rear part of the sheet passes between the rolls I, H the speed of the roll I is gradually retarded so that the sheet is slowed down as its rear edge passes from between the delivery rolls and the sheet is thus brought into accurate position against the front gages.

The supporting bars G and the delivery rolls H, I are mounted in a frame, the rear end of which is pivoted to the brackets E and the front end of which is supported upon bolts K which rest upon the feed board F so that the frame may be swung back to give access to the front end of the feed board and the devices located under it. This pivoted frame is composed of side bars K' provided with brackets K², K³ at their opposite ends which are connected by cross-rods K⁴, K⁵. The brackets K² are pivoted upon a cross-rod E⁶ connecting the brackets E. The supporting bars G are secured upon the cross-rod K⁴ and their front ends rest upon the rear end of a plate F' secured to the front end of the feed board F, the bars being so arranged that their upper surfaces are flush with and form a continuation of the upper surface of said plate.

The rolls I may be driven at a constant high rate of speed during the major portion of the travel of the sheet between the roller H and I and then gradually slowed down as the sheet comes into position at the front gages by any suitable driving mechanism. I prefer however to effect the slowing down of the delivery rolls by connecting the driven delivery roll with its driving gear by means

of intermediate gearing which may be moved in the direction of movement of the driving gear at the proper time so as to modify the motion transmitted from the driving gear to the roller.

In order to effect the retardation of the delivery rollers in as short a time and with as little movement of the movable part of the gearing as is practicable, I also prefer to introduce the movable gearing between the driving gear and a driven gear which is connected with the delivery rolls, and to so construct and arrange the gearing that the driven gear is rotated in the opposite direction from the driving gear by the intermediate gearing.

A simple and efficient form of gearing embodying both of these features which I prefer to employ in driving the delivery rolls, is shown in the drawings, more particularly in Figs. 2, 4 and 6. As shown in these views the tape drum C² is provided at one end with a pinion i which engages a gear i' to which is secured a bevel gear i². This bevel gear i² forms the driving gear for transmitting motion to the driven roll I of the delivery rolls. The connected gears i', i² are loosely mounted on a sleeve i³ secured in one of the brackets E. The driven gear which is connected with the roller I is a bevel gear i⁴ arranged in front of the gear i² and connected to be driven therefrom and in the opposite direction by an intermediate bevel pinion i⁵. The intermediate gearing between the driving gear i² and the driven gear i⁴, which in this construction consists of the pinion i⁵, is mounted upon a carrier i⁶ pivoted upon the shaft i' to which the gear i⁴ is secured so that the carrier may swing about the axes of the gears i² and i⁴. The movements of the carrier i⁶ are effected by means of a cam i⁸ secured to a continuously running cam shaft i⁹ and engaging one end of a bell-crank lever i¹⁰, the other end of which is connected by a rod i¹¹ with the carrier. The lever i¹⁰ is held in engagement with the cam by means of a spring i¹¹. While the lever i¹⁰ rides on the concentric part of the cam i⁸ the carrier i⁶ remains stationary and the gear i⁴ is driven at the same speed as the gear i². During this time therefore the roll I is driven at a constant speed and the gearing between the drum C² and the roll I is so proportioned that the surface speed of the roll is the same as the surface speed of the tapes D which pass over the drum C². When the end of the lever i¹⁰ passes from the high part of the cam i⁸ to the low part, the carrier i⁶ is moved about the axis of the gear i² in the direction of the rotation of said gear thus counteracting the action of the gear i⁴ upon the pinion i⁵ so that the speed of rotation of the pinion i⁵ is reduced. For instance if the pinion i⁵ is moved at the same speed at which the gear i² is traveling, the rotation of the pinion i⁵ upon its axis would be stopped.

When the pinion i^5 is moved in the direction of rotation of the gear i^2 it is also moved in a direction opposite to the rotation of the driven gear i^4 and as the gear i^4 is driven through the pinion i^5 this movement tends to slow down the gear i^4 . By arranging the pinion i^5 between a driving and a driven gear moving in opposite directions and moving the pinion about the axes of these gears, the effect of the movement is doubled. For instance, if the pinion i^5 were moved at the rate at which the gear i^2 is traveling, the pinion would have no rotation upon its axis and would therefore carry the gear i^4 with it in the same direction in which the pinion moves and at the same speed, or in other words this movement of the pinion would cause the gear i^4 to be rotated in the opposite direction to its normal movement and at the same speed. If it is desired to stop the roll i^8 therefore, the carrier i^6 should be moved in the direction of rotation of the gear i^2 and at half the speed at which said gear is traveling. By thus multiplying the effect produced by the movement of the swinging carrier and intermediate gearing carried thereby, the roller I may be rapidly retarded and in a short space of time. This feature also enables the use of a simple connection between the carrier and cam shaft and the use of a small cam upon the cam shaft.

The connection between the gear i^4 and the delivery rolls I are so arranged and constructed as to permit the adjustment of the rolls toward and away from the front gages and so as not to interfere with the swinging back of the front frame when it is desired to get at the front of the feed board. The shaft i^7 to which the gear i^4 is secured extends through the sleeve i^9 and is provided with a gear i^{12} which engages a gear i^{13} loosely mounted on the bar E^6 about which the front frame swings. The gear i^{13} is secured to or formed integral with a spiral gear i^{14} which engages a similar gear i^{15} secured to a shaft i^{16} which extends parallel to the side bars K' of the front frame. The roller I is driven from the shaft i^{16} by means of spiral gears i^{17} one of which is splined to slide upon the shaft i^{16} and the other of which is secured to the shaft i^{16} which carries the delivery rolls.

In order that the rolls I , H may be adjusted toward or away from the front gages so as to be in proper relation thereto for sheets of different length, these rolls are mounted in carriages I' adjustably mounted on the side bars K' and connected by a rod or shaft I^2 . By sliding the carriages I' on the rods K' the position of the delivery rolls may be varied as desired. The carriages may be adjusted in unison by forming pinions on the cross shaft I^2 to engage rack teeth formed on the under side of the bars K' , the adjustment of the carriages being effected by turning the shaft and the carriage being held in adjust-

ed position by friction or any suitable clamping device.

The rolls H are pressure rolls driven by frictional engagement with the rolls I or with the sheets passing between them and these rolls are mounted in arms H' pivoted to lugs H^3 depending from collars H^3 secured to a cross rod I^3 connecting the brackets I' .

What I claim and desire to secure by Letters Patent is:—

1. The combination of sheet conveying surfaces, mechanism for driving said surfaces at a substantially constant speed during the major part of their action on the sheet and then gradually retarding said speed just previous to the release of the sheet by said surfaces.

2. The combination of sheet conveying surfaces, traveling sheet conveyors delivering sheets to said surfaces, mechanism for driving said surfaces at the speed of the traveling conveyors during the major part of their action on the sheet and then gradually retarding said surfaces as the rear of the sheet passes between them.

3. The combination of traveling tapes for conveying sheets, delivery rolls to which said tapes deliver the sheets, mechanism for driving said rolls at the speed of the tapes and gradually retarding said rolls as the rear of the sheet passes between them.

4. The combination of traveling tapes for conveying sheets, delivery rolls to which said tapes deliver the sheets, front gages, mechanism for rotating said rolls at the speed of the tapes to bring the sheets near the front gages and then gradually retarding said rolls.

5. The combination of front gages, sheet conveying surfaces for delivering sheets to the front gages, mechanism for driving said surfaces at a substantially constant speed during the major part of their action on the sheet and then gradually retarding them as the sheet is brought to the front gages.

6. The combination of front gages, sheet conveying surfaces for delivering sheets to the front gages, mechanism for driving said surfaces at a substantially constant speed during the major part of their action on the sheet and for gradually retarding them during their action upon the rear end of the sheet.

7. The combination of front gages, delivery rolls for delivering sheets to the front gages, mechanism for driving said rolls at a substantially constant speed during the major part of their action on the sheet and for gradually retarding them during their action upon the rear end of the sheet.

8. The combination of front gages, sheet conveying surfaces for delivering sheets to the gages, gearing through which motion is transmitted to said surfaces, a driving member moving at a uniform speed, and mechanism for causing a relative movement be-

tween the driver and gearing as the sheet comes to the front gages.

9. The combination of front gages, sheet conveying surfaces for delivering sheets to the gages, a driving member rotating at a uniform speed, gearing through which motion is transmitted to said surfaces, and mechanism for intermittently moving said gearing in the direction of rotation of the driving member to slow down the conveying surfaces as the sheet comes to the front gages.

10. The combination of front gages, sheet conveying surfaces for delivering sheets to the gages, a driving member, a driven member through which motion is transmitted to said surfaces, intermediate gearing between said members for transmitting motion from the driving to the driven member and in the opposite direction, and mechanism for moving said intermittent gearing to slow down said surfaces as the sheet comes to the front gages.

11. The combination of front gages, sheet conveying surfaces for delivering sheets to the gages, a driving gear rotating at a constant speed, gearing connecting said driving gear and conveying surfaces including a movable gear engaging the driving gear, and mechanism for moving said gear about the axis of the driving gear to slow down the conveying surfaces as the sheet comes to the front gages.

12. The combination of sheet conveying surfaces, a gear connected to transmit motion thereto, a pinion driving said gear and movable about the axis thereof, and mechanism for intermittently moving said pinion about the axis of said gear to slow down the conveying surfaces at intervals.

13. The combination of front gages, sheet conveying surfaces for delivering sheets to the gages, a driving gear, a pinion engaging the same and movable about the axis of the

gear, connections between the pinion and conveying surfaces for transmitting motion thereto, and mechanism for moving said pinion about the axis of the gear to slow down the conveying surfaces as the sheet comes to the front gages.

14. The combination of sheet conveying surfaces, a driving gear, a driven gear connected with the surfaces to transmit motion thereto, intermediate gearing rotating the driven gear in a reverse direction, and mechanism for intermittently moving said intermediate gear about the axis of the gears to slow down the conveying surfaces at intervals.

15. The combination of sheet conveying surfaces, a gear i^1 connected therewith, a driving gear i^2 , a pinion i^3 connecting said gears, and mechanism for intermittently swinging said pinion about the axis of said gears.

16. The combination of sheet separating mechanism, a pivoted conveyer frame, conveyer tapes mounted therein, a front frame pivoted to the front end of said conveyer frame, delivery rolls carried by the front frame, gearing for driving said rolls comprising a gear concentric with the pivot of a front frame.

17. The combination of sheet separating mechanism, a pivoted conveyer frame, conveyer tapes mounted therein, a front frame pivoted to the front end of said conveyer frame, delivery rolls carried by the front frame and adjustable longitudinally thereof, and mechanism for driving said rolls.

In testimony whereof I have affixed my signature, in presence of two witnesses.

HENNING HALLSTREAM.
